FIG. 5.

UNITED STATES PATENT OFFICE.

MATTHEW ROBERT MOORE, OF INDIANAPOLIS, INDIANA.

STEAM-ENGINE.

SPECIFICATION forming part of Letters Patent No. 591,485, dated October 12, 1897.

Application filed May 12, 1896. Serial No. 591,270. (No model.)

To all whom it may concern:

Be it known that I, MATTHEW ROBERT MOORE, a citizen of the United States, residing in Indianapolis, Marion county, in the State of Indiana, have invented a certain new and useful Improvement in Steam-Engines, of which the following is a specification.

The object of the invention is to secure a quicker and more complete opening and a more prompt closing of the valves than is obtainable by any of the direct mechanically-connected or releasing valve-gear now in use, resulting in a better distribution of the steam and a saving in the power required to operate the valves.

My improvement is especially adapted for high-speed engines. In all ordinary cut-off valve gears the extent of valve-opening varies with the point of cut-off whether the mechanism be operated by an eccentric of variable throw, a pair of eccentrics with a shifting link, an adjustable cam, or any other means known to me of holding the valve in permanent mechanical connection with the means of operating it. The same difficulty is met with if the engine be of the Corliss class, operated by a releasing-gear, where the valve-stem is periodically caught, pulled open, and released and closed by some form of drop motion. When cutting off early, the amount of opening is small, resulting in a cramping of the current of steam and producing the evil known as "wiredrawing." This is especially serious in quick-moving engines, causing a great reduction of pressure in the cylinder and a consequent loss of power. My invention is designed to completely avoid this objection, giving at every degree of cut-off a full opening of the valve, which is maintained until the proper point of stroke is reached, when practically instant closure follows.

The accompanying drawings form a part of this specification, and represent what I consider the best means of carrying out the invention.

Figure 1 is a side elevation, on a small scale, giving an outline of the governor and the shifting eccentric. Fig. 2 is a diagrammatic representation of my improved valve-gear, merely illustrating its mode of action as applied to a four-valved engine. The engine-

valves (not shown) may be any form of slide-piston or puppet-valve, driven by the reciprocating motion of the valve-piston. Fig. 3 is a vertical section of a portion showing the parts in the correct position. Fig. 4 is a corresponding side elevation partly in vertical section. Fig. 5 shows in side elevation an application of the invention to a four-valved engine having grid slide-valve moving transversely to the main cylinder. Fig. 6 is a corresponding plan view partly in horizontal section. Fig. 7 is a side elevation showing the application of my invention to an engine having Corliss valves. Fig. 8 is a corresponding plan view of a portion, and Fig. 9 a peculiar double section on a larger scale. It shows a part of two vertical sections taken on the lines 8 8 and 9 9, respectively, in Fig. 7. The center of this figure is a section through the action-valve and its adjuncts on the line 8 8, and the parts of the figure surrounding such section show a section on the line 9 9.

I have shown the style of governor and shifting eccentric set forth in the patent to me dated May 26, 1885, No. 318,782, and prefer to use such.

Similar letters of reference indicate corresponding parts in all the figures where they appear. Parts which are closely related take the same letter, distinguished by supernumerals.

For convenience of description I will use the word "steam" to denote any vapor or gas working mechanically by its pressure. I will use the terms "engine steam-valve" and "engine exhaust-valve" to designate, respectively, the ordinary valves which admit the operating fluid to the cylinder of an engine and permit its escape therefrom. I will use the term "trunk-piston" to indicate a piston having two diameters and the term "trunk-cylinder" to denote a corresponding cylinder of two diameters and proper length, in which the trunk-piston works. I will use the terms "steam action-valve" and "exhaust action-valve" to designate the small supplementary valves which are worked by the engine and distribute the steam to the trunk-pistons which operate the engine's steam and exhaust valves, respectively.

Referring now to the drawings, A is the fixed framing and casing. B' is a valve-rod

operated by the variable eccentric C, controlled by the governor B, and D is an action-valve moved by the valve-rod B' to varying extents. These parts operate in the long-ap-
 5 proved manner of automatic speed-governors, diminishing the throw and increasing the advance of the eccentric with respect to the engine's crank as the speed increases, holding constant the point of valve-opening with re-
 10 ference to the stroke, but by changing the valve travel causing the admission of the steam to be cut off earlier as the engine tends to run faster, and vice versa. The action-valve may be very small as compared with
 15 the necessary size of the engine's valves, and the governor and all the connecting parts may be correspondingly light and easily moved, as the work required of them is of small amount.

Fig. 2 represents the steam and exhaust
 20 valves for the out end of a four-valved engine-cylinder, the crank-shaft being supposed to be toward the right hand. The parts, as before mentioned, are drawn somewhat out of position to permit their action to be more
 25 clearly shown.

A' A² is a small trunk-cylinder occupying a position with respect to the engine's cylinder similar to the valve-bonnet through which projects the valve-stem in a Corliss engine.
 30 The bore A' is of about half the cross-sectional area of the bore A².

G II is a trunk-piston fitting the two diameters of the trunk-cylinder, which latter is sufficiently longer than the trunk-piston to permit its required longitudinal movement.
 35 A valve-stem M' connects the trunk-piston to the engine's steam-valve M in the steam-valve chest V. Whenever the engine's throttle-valve is open, the steam-valve chest V con-
 40 stantly contains steam of full pressure. The smaller bore of the trunk-cylinder A' opening directly into the steam-chest V the pressure therein is constantly exerted against the smaller face of the trunk-piston G, thereby
 45 holding the steam-valve M normally in the closed position. A passage w connects the steam-chest with the waist of the action-valve D. This action-valve is a small piston-valve, having a length about twice its diameter, the
 50 middle part being of a smaller diameter, so as to leave an annular space w' surrounding the valve, into which the steam flows through the passage w. The action-valve has a longitudinal reciprocating motion in a suitable
 55 cylindrical valve-chamber containing ports which are covered or uncovered by the motion of the valve.

In the diagram Fig. 2 the parts are shown in the neutral position just before the engine's
 60 piston completes its stroke toward the left. When the action-valve D has moved a little farther toward the left, it will uncover the port and passage w², thus opening a way through the passage w, w', and w² for the steam to enter the larger end of the trunk-cylinder A² and press against the larger face of the trunk-

piston. The passage w³ leading back from the larger end of the trunk-cylinder to the action-valve case being closed by the valve when in the position described the steam ad-
 70 mitted to A² cannot escape.

The annular space X around the trunk-piston communicates freely through the passage x' with the action-valve case, and any steam contained therein can escape. The larger end 75 of the trunk-piston II having about twice the area of the smaller end and both being now pressed upon by steam of the same pressure, motion will ensue and the engine's steam-valve will be opened. To prevent the trunk-piston as it completes its stroke violently striking the bottom of the trunk-cylinder, the port x' opens a little above the bottom of the annular space X, so that it is closed by the trunk-piston just before reaching the end 85 of its stroke, and the piston cushions on the imprisoned steam and comes gently to rest.

The valve M having been opened, as de-
 90 scribed, will remain fully open until the action-valve D completes its stroke toward the left and returns to the position shown, closing the inlet-passage w², leading to the larger part of the trunk-cylinder A². Then a slight further movement toward the right opens the passage w³. The steam now escaping, the 95 constant force of steam of full pressure on the smaller end of the trunk-piston G is opposed only by a much smaller back pressure on the larger end and is assisted by the like back pressure on the shoulder of the trunk-piston in the annular space X. Motion again ensues and the engine steam-valve M is sud-
 100 denly closed. To prevent the trunk-piston striking at the end of its outer stroke, a simi-
 105 lar steam-cushion is formed by making the port w³ to open a little within the outer end of the trunk-cylinder A², so that the trunk-piston overruns and closes it before reaching the end of its stroke, and the passage w² being now closed by the action-valve D the rem-
 110 tant of steam in A² cannot escape and so cushions the trunk-piston. These movements for opening and closing the engine's steam-
 115 valve occur regularly, as described, at periods determined by the motion of the action-valve D, which, as before mentioned, receives its motion from an eccentric under the control of a governor, which causes the opening move-
 120 ment to occur constantly at the beginning of the engine's stroke, and to close at any point when steam enough has been admitted to the cylinder to carry the engine's load and main-
 125 tain the speed determined upon. It will be observed that the action-valve D in its relation to the ports w² and w³ has practically no lap or only just enough to enable it to cover both ports when in the center of its travel.

The slightest movement in either direction will open one or the other, keeping the remaining one closed. At no point of the valve 130 travel can both be open to the same or connecting chambers. In consequence of this

provision the position of the engine's steam-valve is instantly changed whenever the action-valve D passes its central position.

The steam which has done work in operating the engine's steam-valve, as described, though much weakened in pressure by condensation and expansion into chambers of larger volume, still retains strength enough to operate the engine's exhaust-valves. To avail of this, the two ends of the steam-action-valve chamber x^2 and x^4 are connected by the passage x^3 , the coupled pipes x^5 , and passage x^6 with the chamber of the exhaust action-valve O. This action-valve and its case are exactly like the steam action-valve D, except that the left or working end of valve O is a little longer, so as to afford considerable lap over the two ports y' and y^2 , which the valve controls, the purpose of which will be described hereinafter. The engine's exhaust-valve N is provided with a bonnet bored out to form a trunk-cylinder containing a trunk-piston connected by a valve-stem with the exhaust-valve, in all respects like the devices just described for operating the engine's steam-valves, except that the valve-stem, it must be understood, is attached on the exhaust side of the valve, so that whatever style of valve be employed the space Z, corresponding to the steam-valve chest V, is in direct communication with the exhaust-pipe, as V is with the steam-supply pipe of the engine, and the smaller end of the exhaust trunk-cylinder A³ is filled with exhaust-steam of little or no pressure. This is illustrated in Fig. 3, which shows a grid slide-valve.

The spaces A³, A⁵, and x¹⁰ at the ends and middle of the exhaust trunk-cylinder are connected by passages y, y', y², and x⁹ with the case of the exhaust action-valve O. Steam released from the steam trunk-cylinder A² flows freely down through the exhaust-action-valve case and passages x⁵ to the annular space x¹⁰, where it presses constantly against the shoulder of the exhaust trunk-piston and holds, by means of the valve-stem N', the engine exhaust-valve in the closed position. The diagram Fig. 2 shows the position of the parts just before the completion of the engine's piston stroke toward the left. The exhaust-valve has closed and compression of the steam remaining in the engine-cylinder is taking place. The action-valve O is now moving toward the left, and being driven by the same eccentric that operates the steam action-valve D will move in like manner to the end of its travel and return presently to the position shown. On account of the slightly-greater lap of the valve O, however, the port y will not be uncovered when the steam action-valve D uncovers the port w³ to shut the steam-valve. The engine exhaust-valve will therefore remain closed until near the completion of the engine's piston stroke toward the right. Then the action-valve O, uncovering the port y², allows steam to flow

through the passage against the larger end of the exhaust trunk-piston S, forcing it to move and open the engine's exhaust-valve N. The action-valve O, completing its travel toward the right, returns, again covering the port y and holding the engine's exhaust-valve open by the imprisoned steam until at the completion of a revolution of the engine it again reaches the position shown, uncovering the port y' and permitting the steam in the trunk-cylinder A⁵ to escape to the waist of the action-valve O. This waist-chamber is always in communication, through the passage y², with the exhaust-space Z of the engine-exhaust, so the steam can freely escape, and the trunk-piston R S, impelled by the pressure of the steam in the annular chamber x¹⁰, at once moves outward and closes the exhaust-valve N. Provision is made for cushioning the movements of the trunk-piston R S by the position of the ports connecting the passages y' and x⁹ with the trunk-cylinder A⁵, which act in the same manner as the like provisions for cushioning the steam-valve trunk-piston G H.

In view of the fact that there is steam of a working pressure constantly acting on the smaller ends G of the trunk-pistons and that the steam imprisoned in advance of each in the cushioning by the pistons passing the ports x' x⁹ retains its pressure ready to spring out again as soon as the pressure is withdrawn from the larger ends H of the trunk-pistons it may not be necessary to make any other provision for the return of the pistons; but to cover any possible default I provide the passages p' p², connecting the bottoms of the annular chambers x x¹⁰ with the action-valve cases arranged as shown, so that the several passages p' p² will be closed each by the corresponding action-valve D or O before steam is admitted to the larger ends of the trunk-pistons. I thus prevent the escape of the cushioning steam, but the passages are uncovered again to permit steam to enter when the valves uncover the exhaust-ports w³ y². The effect of these extra passages p' p² is the same as the doubled connection to the larger ends of the trunk-pistons, the steam entering through one passage and being discharged through the other. It will, of course, be understood that the passage p² has no connection with the passage w³.

In recapitulation the spaces V, w, and w' are constantly filled with steam of full pressure, which, for the purpose of illustration, may be assumed to be one hundred pounds per square inch. The spaces X, x', x², x³, x⁴, x⁵, x⁶, x⁷, x⁸, x⁹, and x¹⁰ are filled with steam that has done work in moving the trunk-piston G H, and by reason of expansion and cooling has fallen to some lower pressure, which may be assumed as fifty pounds per square inch. The spaces y² and Z being constantly open to the engine's exhaust-chamber can never contain anything more than a slight back pressure, which in a

simple non-condensing engine may be placed at two pounds per square inch above the atmospheric. The areas of the smaller ends of the trunk-pistons G and R and the shoulders X and X¹⁰ may be assumed to be six square inches and the areas of the larger ends H and S may be taken as twelve inches. Any other dimensions might be assumed, and the dimensions will, in practice, depend on the size of the engine. There will, therefore, be, when the valve-gear is in the position shown in Fig. 2, a force of $(100 \times 6 - 50 \times 6) - (50 \times 12) - 300$ pounds, tending to close and hold shut the steam-valve M. When the action-valve 15 has moved a little toward the left and uncovered the port w², there will then be a force of $(100 \times 12) - (100 \times 6 - 50 \times 6) - 300$ pounds, tending to open the steam-valve. Similarly the exhaust-valve N will be held closed by a force of $(50 \times 6 - 2 \times 6) - (2 \times 12) - 288$ pounds until the action-valve O uncovers the port y, when the exhaust-valve will be opened by a force of $(50 \times 12) - (50 \times 6 - 2 \times 6) - 288$ pounds.

25 From the well-known action of a piston-valve driven by a shifting eccentric under the control of a shaft-governor it will be readily understood that the action-valve D may be so adjusted as to always uncover the port w² and cause the opening of the steam-valve M at the beginning of the engine's stroke toward the right. It will also be understood that when the engine has made exactly half a revolution the steam action-valve at the right end 30 of the cylinder, Figs. 5 and 6, driven by the same eccentric, will admit steam to open the steam-valve at that end to begin the return stroke. These two points are constant, however the throw of the eccentric, the valve 35 travel, and the consequent point of cut-off may vary. Now since the exhaust action-valves are also driven by the same eccentric it will be seen that the valve O may be so adjusted as to uncover the port y' just a little 40 in advance of the uncovering of the port w² by valve D, thus causing the engine exhaust-valve N to close a little before the end of the leftward stroke of the engine's piston, producing the required compression to fill the 45 engine's clearance-spaces and enable it to pass the center smoothly. It will also be seen that so much lap may be given the valve O that the port y will not be uncovered until the engine has made about half a revolution, 50 the uncovering taking place just before the completion of the engine's stroke toward the right, thus opening the exhaust-valve N and releasing the steam a little in advance of the opening of the right-end steam-valve by the 55 action-valve at that end. Thus the left or releasing corner of the exhaust action-valve O stands in about the same relation to the right-hand steam action-valve that its inner or compression corner does to the left-hand steam action-valve D. Therefore the steam admission-points being constant the release and compression points must be likewise constant.

The points of release and compression are adjustable to a sufficient extent by merely changing the positions of the nuts O² O³, Fig. 70 5, and thus varying the length of the exhaust-action-valve rod O'. If the action-valve O be adjusted toward the left, compression will be increased and release retarded. If adjusted toward the right, the reverse effect will be 75 produced. If it be required to hasten or retard both release and compression, the advance of the eccentric may be changed and the effect on the steam-valve corrected by changing the length of the steam-action-valve 80 rod. Figs. 3 and 4 show, partly in section, the same valves, &c., which are represented in Fig. 2. The ports and passages are here somewhat difficult to trace, but their proper relations will be understood from the description 85 already given.

Modifications may be made without departing from the principle or sacrificing any of the advantages of my invention. In Figs. 7 and 8 is shown an engine-cylinder having 90 the well-known rocking or Corliss valves, to which my invention is applied in a modified form. The valves are operated through the medium of cranks and rods connecting them with trunk-pistons moving in four cylinders 95 joined in a single casting, which occupies the position of the "wrist-plate" in the ordinary Corliss valve-gear. The steam distribution to these pistons is effected by a single-action valve, which alternately admits live steam to 100 and exhausts it from the larger ends of the trunk-pistons at proper times respectively to give outward motion to the pistons and the valves attached thereto, the return motion being produced by a constant pressure of 105 steam upon the shoulders of the trunk-pistons, which have about half the area of the larger ends. The construction and arrangement of these parts are more clearly shown in the sectional diagram Fig. 9. The four cylinders are bushings inserted in a hollow casting, the annular spaces surrounding the bushings being in communication through a passage a with the live-steam passage of the engine-cylinder, so that the valve-moving cylinders 110 are surrounded with steam and are certain to be quickly and thoroughly heated up to the working temperature. In each cylinder is a trunk-piston, the trunks passing out through a suitable packing, so that each 115 piston presents two unequal faces to the pressure of steam admitted to its cylinder. Through a port b in the lower side of each cylinder the steam passes freely and bears with a constant pressure against the shoulder 120 of the trunk-piston. The effect of such pressure is normally to drive the trunk-pistons to the bottoms of their cylinders and to hold the engine's steam-valves closed and its exhaust-valves open. Ports and passages for steam 125 connect the inner end of each cylinder with the chamber of an action-valve, which is represented in the drawings as bolted upon the casting containing the cylinders. These pas-

sages are doubled for the purpose of cushioning the motion of the trunk-pistons, steam being admitted through the inner passage of each pair and exhausted through the outer one, which is so placed that the trunk-piston overruns and closes it before it can strike the bottom of the cylinder. For the like reason the ports *b b* are placed at a little distance inward from the outer ends of the cylinders. A 10 passage leading from the bottom of the hollow casting containing the cylinders enters the action-valve case and admits steam through its central port *c*. By taking this passage from the bottom of the casting, the passage 15 *a* entering the top, circulation is promoted and the spaces prevented from filling up with water of condensation.

Within the action-valve case, controlling the ports therein, is a piston-valve, which may 20 be made in a single piece, similar to *D* and *O*, Fig. 2, but the one shown in Fig. 9 is a modified form, with means for adjustment in length. This form of action-valve consists of two disks, one of which is fastened firmly 25 to the end of the valve-rod and the other is mounted on a hollow rod surrounding the valve-rod proper and connected thereto by a pair of jam-nuts, so that the disks can be moved toward or from each other, as occasion 30 may require, and firmly fastened in the desired position. The steam-ports in the upper side of the action-valve case are so arranged that the action-valve has no lap over the steam-ports and exhaust-ports leading to and 35 from each steam-valve cylinder, so that the closing of one port is immediately succeeded by the opening of the other. The opening of the steam-ports in the lower side of the action-valve case, connecting with the exhaust-40 valves cylinders, are so arranged that the action-valve will open them just before opening the steam-valve ports for the corresponding end of the engine-cylinder, to the end that compression and release may precede admission, and the exhaust-ports are so placed as 45 to give sufficient lap to serve the purpose before described. The steam which has done its work in moving the trunk-pistons and the attached engine-valves is discharged from 50 the ends of the action-valve case down through the passage *d* into the exhaust-passage of the engine.

The *modus operandi* of the device will be readily understood from the drawings, in the 55 light of the description already given.

The features which are common to these different forms of my steam-actuated valve-gear and which constitute the gist of my invention are the valve-moving pistons having 60 faces of different areas, with constant pressure upon their smaller faces tending to open or close and hold in such position the engine-valve connected therewith, in combination with action-valves actuated by the motion of 65 the engine, under the control of a speed-governor, admitting and releasing the steam-

pressure to and from the larger faces of the pistons through ports so arranged as to obtain constant lead opening and variable cut-off for the engine's steam-valves, and for its 70 exhaust-valves practically constant release and compression.

I claim as my invention—

1. In a valve-motion for steam-engines, a trunk-cylinder and a trunk-piston, and connections from the latter to a main valve of the engine, in combination with passages for steam, admitting constant pressure to the smaller face of the trunk-piston, and means as an action-valve with ports and passages 80 for alternately admitting and releasing the steam-pressure to and from the larger face of the trunk-piston to operate the main valve, together with variable mechanism operating the action-valve by the motion of the engine, 85 substantially as herein specified.

2. In valve-actuating gear for steam-engines, a trunk-cylinder containing a trunk-piston adapted to be driven alternately in opposite directions by the pressure of steam on 90 one of the end faces and on an annular area at the waist, connected with a main valve and with an action-valve, and variable mechanism as a shifting eccentric *C* and with means as the governor *B* for variably operating the action-valve by the motion of the engine, all combined and arranged for joint operation as herein specified.

3. In a valve-actuating gear for steam-engines, a trunk-cylinder containing a trunk-piston adapted to be driven alternately in opposite directions by the pressure of steam on 100 one of the end faces controlled by ports and passages and the action-valve *D*, the said trunk cylinder and piston forming at the 105 waist an annular area, together with ports and passages *x'* and *p'*, communicating with said area, and with the action-valve, and adapted to be closed to enable the steam in the area to cushion the piston, substantially 110 as herein specified.

4. In valve-actuating gear for steam-engines, a trunk-piston working in a trunk-cylinder having ports *w'* and *x'*, arranged to cushion the steam and cause such piston to 115 be arrested gently at the end of its movement, the piston being connected with a corresponding main valve in combination with an action-valve, variable mechanism as a shifting eccentric *C*, and means as a governor 120 *B* for variably operating the action-valve by the motion of the engine arranged for joint operation as herein specified.

5. A valve-motion for steam-engines comprising two trunk-pistons working in corresponding trunk-cylinders and connected to two main valves of the engine, and provisions as the shifting eccentric and governor and connections to the steam action-valve *D*, and exhaust action-valve *O*, and the requisite ports for operating one by the pressure of live steam and the other by the pressure 125 130

of the exhaust from the first, all substantially as herein specified.

6. A valve-motion for steam-engines, comprising four separate main valves, and four operating-pistons therefor, working in four corresponding cylinders, and four action-valves for operating such pistons from a single shifting eccentric, in combination with each other and with a governor and provisions as the nuts O^2 , O^3 , for independently adjusting the position of each action-valve

relatively to such eccentric, all arranged for joint operation substantially as herein specified.

In testimony that I claim the invention above set forth I affix my signature in presence of two witnesses.

MATTHEW ROBERT MOORE.
